(57) **CLAIM**

The ornamental design for a multi-functional chair, as shown and described.

DESCRIPTION

FIG. 1 is a top perspective view of a multi-functional chair, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a bottom perspective view thereof;

FIG. 9 is a top perspective view showing the multi-functional chair, in configuration of use; and,

FIG. 10 is an enlarged view of detail 10 in FIG. 1.

All the broken lines in the drawings depict portions of the multi-functional chair that form no part of the claimed design.

The large evenly-spaced dashed lines encircling portions of the multi-functional chair in FIG. 1 and illustrated in the enlarged view in FIG. 10 form no part of the claimed design. The small evenly-spaced dashed lines depict portions of the multi-functional chair that form no part of the claimed design.

1 Claim, 10 Drawing Sheets
